UNITED STATES PATENT OFFICE.

FRANZ SKAUPY, OF BERLIN, GERMANY, ASSIGNOR, BY MESNE ASSIGNMENTS, TO GENERAL ELECTRIC COMPANY, OF SCHENECTADY, NEW YORK, A CORPORATION OF NEW YORK.

ELECTRIC DISCHARGE TUBE.

Application filed August 30, 1921, Serial No. 497,028, and in Germany July 4, 1919.

This invention relates to discharge tubes which operate with a glow discharge and may be used for illumination purposes (as a lamp with glow discharge) or in the transmission 5 of intelligence (as a vacuum tube for instance) or for similar purposes and which can be run with an exceptionally low voltage without necessitating the use of electropositive metals for the cathode, or which, in cases 10 in which such metals are employed, enables the discharge voltages hitherto required to be considerably reduced.

The invention will be more readily understood by reference to the accompanying drawing, in which Fig. 1 shows a tube with the 15 cathode in net form while the anode is in the form of a wire projecting into the hollow cathode.

Fig. 2 shows both the anode and the cathode 20 each in the form of a net. This form of construction is especially adapted for use in connection with alternating currents in which case both electrodes become luminous.

In accordance with the invention the reduction 25 of the discharge voltage is obtained by using metals of a specially high degree of purity for the cathode which, after they have been subjected to the manufacturing process—which may involve annealing or melting 30 in a vacuum or in an indifferent atmosphere—are almost free of gas. The degree of subdivision of the metal of the electrode should preferably be such that the amount of gas that remains at the end of the manufacturing 35 process is so small that even the last traces of it are capable of being removed from the tube, so that after the lamp is melted off the discharge of gas should not exceed the amount that can be removed by using the lamp for a 40 short period and through the automatic self-purifying action of the electrodes and the gaseous contents which then takes place at the desired low discharge voltage.

The terminal voltage with which this tube 45 can be made to operate, depends not only on the material used for the electrodes, but also on the nature of the gas. By using neon it is easy in this way to reduce the terminal voltage to less than 140 volts if very pure or substantially chemically pure iron or tungsten 50 wire is used for the electrodes. By this means it is even possible to reduce the terminal voltage to less than 100 volts so that tubes of this kind can be run off 110 volt supply mains. 55 If filling of argon, krypton and xenon are

used the terminal voltages can be made still lower. This is the more remarkable because the drop of potential at a cathode of iron for example in neon should, according to the present opinion of experts, be about 180 volts. 60

The necessary high degree of subdivision of the matter, which in itself already contains very little gas, is most readily obtained by using woven or knitted metal netting, or coiled thin wires or the like. The purification 65 of these novel metal electrodes, which are almost devoid of gas in any case, is accomplished in accordance with the invention partly by filling the discharge tube with the aid of a pump with gas at the usual pressure 70 (e. g. 10 mms. of argon or 10 mms of neon) and then applying an excessive voltage, and finally pumping off the gas filling once or twice which has been made impure by the application of the excessive voltage, and partly 75 by using the completed tube at the factory for a short time until the terminal voltage becomes constant.

The electrodes manufactured in accordance with the invention can also be advantageously 80 employed in vacuum protective devices or lightning arresters. By this means the arresters can be made to operate at the said low voltages. Previous attempts have been made to obtain the same result in vacuum arresters 85 by using, in combination with a filling of noble gas, electrodes made of common metals which are easily volatilized by, and sensitive to, electric currents. Metals of this kind are alkali metals for instance or their alloys mixed 90 with each other or with metals. But such metals are extremely inconvenient in the process of manufacturing the tubes and very dangerous in use. For this reason the substitution of these metals by metals which are 95 much nobler and more difficult to melt, such as tungsten or iron (which, in accordance with the invention, are rendered extraordinarily pure) constitutes a considerable advance on account of the above-described disadvantages being avoided. 100

With vacuum arresters provided with electrodes according to the invention and with a filling of noble gas a discharge voltage may be obtained which is almost as low as in the 105 case of such electrodes made of alkali metal.

By using the novel electrodes in vacuum arresters the additional advantage is obtained that the arresters operate noiselessly. Hence their operation does not result in dis- 110

turbining noises such as clicks in the telephone receivers of telephone systems in which such arresters are employed in large numbers. It will be seen that by using substantially 5 chemically pure electrodes and by using care to have these electrodes free from occluded and adsorbed gases, I obtain an electric vacuum tube which may be used to operate at a very low voltage.

10 I claim:—

An electric discharge device comprising a

sealed container, an attenuated inert gas therein, non-alkaline electrodes therefor consisting of fine wire mesh free from occluded non-inert gases whereby a glow discharge 15 may be operated between the electrodes at voltages of the order of one hundred volts, the area of said electrodes being great enough to permit of the indefinite continuance of such glow discharge at said voltage. 20

In testimony whereof I affix my signature.

FRANZ SKAUPY.
